(57) CLAIM

We claim the ornamental design for a pocket, as shown and described.

DESCRIPTION

FIG. 1 is a front view of a pocket, showing our new design; FIG. 2 is a left front perspective view thereof; and, FIG. 3 is a right front perspective thereof. The dashed lines are included for illustrating environmental structure and form no part of the claimed design.

1 Claim, 3 Drawing Sheets

FIG. 1

FIG. 3
